METALLIC WINDOW CONSTRUCTION

Joseph Ferruggia, New York, N. Y.

Application December 30, 1938, Serial No. 248,587

5 Claims. (Cl. 189—66)

The present invention relates to a metallic window construction and has for its primary object to provide a metallic window frame adapted to accommodate upper and lower sash and in which the sash embodies an inner swingably mounted frame adapted for swinging movement independent of the sliding movement of the sash.

An important object of the present invention is to provide a window construction of this character which includes spring means for yieldably returning the inner swinging sash to its normally closed position together with locking means for securing the swinging sash into a desired adjustable position; also embodying means for readily securing the swinging frame in its closed position.

A further object of the invention is to provide a sectional swinging frame for the sash within which a plurality of panes of glass may be removably mounted.

Another object is to facilitate the cleaning of the windows as well as to obtain the greatest amount of ventilation which is accomplished by mounting the sash in a manner to swing into a horizontal position.

A still further object is to provide a window frame construction which is strong and durable, neat and attractive in appearance, relatively inexpensive to manufacture and otherwise well adapted for the purposes for which the same is intended.

Other objects and advantages reside in the details of construction as more fully hereinafter described and claimed, reference being had to the accompanying drawings forming part hereof, wherein like numerals refer to like parts throughout, and in which—

Figure 1 is an elevational view showing the inside of the window construction.

Figure 2 is a similar view showing the outside of the window.

Figure 3 is a horizontal sectional view.

Figure 4 is a sectional view of a modified form of tubular frame construction.

Figure 5 is a vertical transverse sectional view.

Figure 6 is a fragmentary sectional view through the connection between the upper and lower sash and showing the locking means therefor.

Figure 7 is a fragmentary sectional view taken on a line 7—7 of Figure 1 and illustrating the locking handle for the swinging sash.

Figure 8 is a fragmentary sectional view taken substantially on a line 8—8 of Figure 1 and illustrating the adjustable locking mechanism for

securing the swinging sash in an adjusted position.

Figure 9 is a similar view taken substantially at right angles to Figure 8.

Figure 10 is a sectional view taken substantially on a line 10—10 of Figure 5.

Figure 11 is an edge elevational view of the sliding and swinging sash.

Figure 12 is a horizontal sectional view of a double window frame embodying the present invention.

Figure 13 is a front elevational view of a modified form of the invention employing a wood frame for the sliding and swinging sash.

Figure 14 is a sectional view taken substantially on a line 14—14 of Figure 13.

Figure 15 is a sectional view taken substantially on a line 15—15 of Figure 13.

Figure 16 is a modified form of locking mechanism for the swinging sash.

Figure 17 is a fragmentary sectional view taken substantially on a line 17—17 of Figure 1 and illustrating an auxiliary locking mechanism for adjustably securing the swinging sash.

Figure 18 is a sectional view of a modified form 23 of tubular construction.

Figure 19 is a front elevational view of a modified form of frame embodying a multiple pane swinging sash.

Figure 20 is a sectional view taken substantially on a line 20—20 of Figure 19.

Figure 21 is a fragmentary sectional view taken substantially on a line 21—21 of Figure 22.

Figure 22 is a sectional view taken on a line 22—22 of Figure 19.

Figure 23 is a detail showing the interlocking connection between the vertical and horizontal frame members of the multiple pane sash, and

Figure 24 is a perspective view of one of the sectional frame members for the multiple pane sash.

Referring now to the drawings in detail and with particular reference to the form of the invention illustrated in Figures 1 to 3 inclusive and Figure 5 of the drawings, the numeral 5 45 designates a metallic window frame construction generally, which includes a sectional tubular side frame 6 and channel top and bottom frame members 7 and 8, the side frame member 6 being recessed in the edge of the wall 9 of the window 50 opening provided therefor. To the inner surface of the side members 6 is secured the parting strip 10 which also extends across the top and bottom frame members and sash guides 11 are also secured to the frame members at the inner and 55

outer edges thereof for slidably accommodating upper and lower sash 12 and 13 respectively.

The sash are of tubular metallic construction as more clearly illustrated in Figure 6 of the drawings and include a swingable sash frame 14 having their opposite side edges secured on square-shaped trunnions 15 and anchored in position thereon by pins 16 inserted through openings 17 in the trunnions.

10 The trunnions 15 are formed on a shaft 18 journaled in the sliding sash, one end of the shaft being rotatably supported in a removable plate 19 suitably secured in position in the side of the sash as clearly illustrated in Figure 9 of the 15 drawings.

A ratchet 20 is formed on the shaft 18 between the teeth of which a latch member 21 is engageable, said latch member being slidably mounted in a bracket 22 and yieldably held in engaged 20 position by a coiled spring 23. A manipulating lever 24 extends from the latch member outwardly through a slotted opening 25 formed in the front surface of the sliding sash member and formed on its outer end with a manipulating knob 26, the inner end of the lever being pivoted as at 27.

A coiled spring 28 is secured at one end to the shaft 18 and has its opposite end 29 bearing against a wall of the tubular sliding sash to yieldably urge the swinging sash in a closed position. The latch member 21 will serve to secure the swinging sash in any desired adjustable position, as will be apparent.

35 The swinging sash 14 is secured in its closed position by a latch member 30 movable into and out of an opening 31 formed in the sliding sash frame, said latch member being secured to a rod 32 journaled in bearing guides 33 and to which rod is secured the ends of a U-shaped 40 handle 34 projecting outwardly through openings 35 in the top of the swinging sash 14, as clearly shown in Figures 6 and 7 of the drawings.

The upper and lower sliding sash are secured 45 in locked position by a bolt 36 carried at the upper portion of the lower sliding sash and having one end engageable in a recess 37 formed in the lower edge of the upper sliding sash, the bolt being provided with a coiled spring 38 for projecting the same into said recess. The other end of the 50 bolt projects outwardly from the sash 13 and is provided with a manipulating knob 39 and the bolt also is provided with a lug 40 movable into and out of position behind the front wall of the 55 sliding sash frame to secure the bolt in either its locked or unlocked position, the bolt being rotatable for movement through a notch 41 in the opening of the sash.

In Figures 15 and 16 I have illustrated a modified form of latch construction for securing the 60 swinging sash to the sliding sash, in this form of the invention the U-shaped handle 42 being provided with an intermediate cross-bar 43 on which the latch 44 is secured for movement into and out of engagement in the opening 45 in the 65 sliding sash 13. The inner ends of the handle 42 are secured to the opposite ends of the rod 46 which is journaled in the bearings 47 and the rod is provided with a coiled spring 48 secured at one end to the rod and having its other end secured to one of the bearings for yieldably urging the latch in engaging position.

The tubular side members 6 of the frame are 70 provided with the usual sash-weight pulleys 49 supported on a bracket 50 secured in the tubular

frame member 6, as clearly shown in Figure 10 of the drawings.

In Figures 13 and 14 a modified form of sliding sash is illustrated which includes a wooden sash frame 51 to the inner edges of which are secured 5 a channel strip 52 within which the inner edge of the frame 51 is inserted so that the side portions 53 of the channeled strips partly enclose the frame. The swinging sash 54 is secured to the strip 52 in the same manner as that previously 10 described.

In Figures 19 and 20 a further modification of the sliding sash is provided and which likewise includes the wooden frame 55 having a wooden strip 56 secured to its inner edge and to which 15 the swinging sash 57 is pivotally secured in the manner as heretofore explained. Yieldable packing strips 58 are interposed between the abutting edges of the strip 56 and swinging sash 57 which 20 form weather strips for the abutting edges thereof.

In Figure 18 I have illustrated a modified form of parting strip for the tubular metallic frame, the frame being indicated at 59 and the parting strip 60 being recessed in a groove 61 formed 25 therein and secured in position by screws or the like 62.

In Figures 21 to 24 inclusive, I have illustrated the swinging sash construction provided with multiple removable panes of a type illustrated in 30 Figure 19. The sash includes a plurality of vertical and horizontal removable strips 63 and 64 respectively, having channels 65 formed in the opposite longitudinal edges thereof for accommodating the edges of the glass panes 66, suitable 35 packing strips 67 being interposed between the glass and the metallic strip.

The end portions of the strips are provided with extensions 68 adapted for engagement in notches 69 formed in adjacent angularly disposed strips as shown in Figure 23, whereby to 40 anchor the horizontal strips to said vertical strips. The top edge of the sash is closed by a channel frame member 70 secured in position by screws 71.

It will be observed that in the several front 45 elevational views of the sash that the same are provided with pivotal mountings along the opposite side edges for the swinging sash, embodying the construction illustrated in Figures 8, 9 and 17, although it will be apparent that only one 50 locking mechanism may normally be required for each swinging sash. However, under certain circumstances, the second locking mechanism may be found necessary, such as while replacing a 55 broken glass so as to secure both edges of the swinging sash firmly, and in the normal use of the window one of these locking mechanisms may be held inactive by moving the lever 24 horizontally in the angular extension 71' formed at the upper end of the slotted opening 25.

It is believed the details of construction and manner of use of the device will be readily understood from the foregoing without further detailed explanation.

Having thus described the invention, what I 65 claim is—

1. A metallic window construction comprising a frame for mounting in a window opening, a pair of sliding sash mounted in the frame, a swinging sash for each sliding sash, spring means 70 yieldably urging the swinging sash in a closed position, a spring projected catch movable outwardly from one free end of a swinging sash and engageable with an adjacent edge of the sliding sash to secure the swinging sash in closed 75

position and a U-shaped actuating handle for the catch projecting from one face of the swinging sash.

2. A metallic window construction comprising
5 a frame for mounting in a window opening, a pair of sliding sash mounted in the frame, a swinging sash for each sliding sash, a spring rotated trunnion carried by the sliding sash forming a mounting for the swinging sash, a spring
10 projected catch movable outwardly from one free end of the swinging sash and engageable with an adjacent edge of the sliding sash to secure the swinging sash in closed position and a U-shaped actuating handle for the catch having its ends
15 pivoted in the swinging sash and having its bight portion projecting outwardly from one face of the swinging sash.
3. A metallic window construction comprising a frame for mounting in a window opening, a pair
20 of sliding sash mounted in the frame, a swinging sash for each sliding sash, a spring rotated trunnion carried by the sliding sash forming a mounting for the swinging sash, a tooth member carried by the trunnion, a spring actuated slidably
25 mounted catch engageable with the toothed member to releasably secure the swinging sash against movement and a manipulating handle pivoted to the swinging sash and connected to said catch for releasing the same, said swinging
30 sash having a slotted opening through which the handle projects and provided with a lateral extension for receiving the handle to secure the catch in disengaged position.

4. A metallic window construction comprising a frame for mounting in a window opening, a pair of sliding sash mounted in the frame, a swinging sash for each sliding sash, a handle pivoted to the swinging sash and projecting outwardly thereof, a lug on an intermediate portion of the handle engaging the sliding sash for securing the swinging sash against movement in the sliding sash, independent catch means for securing the swinging sash in adjusted position
10 in the sliding sash and a spring projected bolt carried by one sliding sash and engaging the other sliding sash for securing the sliding sash against movement.

5. A metallic window construction comprising
15 a frame for mounting in a window opening, a pair of sliding sash mounted in the frame, a swinging sash for each sliding sash, catch means securing the swinging sash against movement in the sliding sash, independent catch means for
20 securing the swinging sash in adjusted position in the sliding sash, a spring projected rotary bolt slidably mounted in one sliding sash and engageable with the other sliding sash for securing the sliding sash against movement, and means carried by the bolt for securing the same in its projected or retracted position, said last named means comprising a laterally projecting lug on the bolt and movable inwardly and outwardly of an opening in the sash and engageable at
25 30 opposite sides of the opening upon a partial rotation of the bolt.

JOSEPH FERRUGGIA.
